UNITED STATES PATENT OFFICE.

NELSON HURD FULTS, OF ADA, OHIO.

AUTOMATIC ROPE-CLAMPER.

SPECIFICATION forming part of Letters Patent No. 769,475, dated September 6, 1904.

Application filed November 14, 1903. Serial No. 181,159. (No model.)

To all whom it may concern:

Be it known that I, NELSON HURD FULTS, a citizen of the United States, residing at Ada, in the county of Hardin and State of Ohio, have invented new and useful Improvements in Automatic Rope-Clampers, of which the following is a specification.

My invention relates to an improved automatic rope tightener and clamer, and more particularly to a device adapted to be used for temporarily compressing and holding a shock of cornstalks or grain while being bound with a band of straw or any suitable material.

The object of my invention is to provide a device of this character by means of which the rope may be adjusted from either direction in order that the shock may not be twisted out of position, as is the case when the rope is adjusted from one direction only, and a device which can be instantly released when the shock is bound.

My invention consists in the arrangement and combination of parts, as will be herein-after more fully described, and pointed out in the claims.

Referring to the drawings, in which similar letters of reference indicate similar parts throughout both views, Figure 1 is a plan view of my invention. Fig. 2 is a side elevation showing the device unlocked.

In the drawings, the letters *a* and *b* represent the two sections of my rope-clamp pivoted or hinged together by a rivet *c*, which rivet also passes through locking device *d*.

35 Journaled in the outer end of said section *a* between extended arms *e* is a pulley-wheel *f*, placed a sufficient distance from the body of said section to form an opening *g* for rope *h*. Rope-guides *i* are formed on said arms *e*.
40 Rising vertically from the inner central portion of section *a* and extending horizontally over section *b* is the locking-lever *k*, by means of which the device is locked and unlocked. In the end of section *b* is formed a longitudinal pulley-slot *l*, having a side opening *m* for the reception of rope *h* and provided with rope-guides *n* and having a pulley-wheel *o*, journaled in said slot a suitable distance from the body of said section to allow an opening 45 *p* for rope *h*. The face of sections *a* and *b*

has raised edges or flanges *q* to form a recess for the reception of locking device *d*, which locking device consists of oppositely-extending arms *s* and *t*, having concaved ends which reach to within a short distance of each pulley. The portion of the clamp between said arms is a substantially oval-shaped slot, through which passes the locking-lever *k*, the clamp being pivotally mounted on the rivet *c*. The said parts can be constructed of malleable 55 or cast iron.

In operation the clamp is first unlocked by raising the lever *k*, which operation lowers the pulley-wheels, thus forcing them from proximity to ends of clamping-arms *s* and *t*. 65 The rope is then knotted at one end to prevent said end from slipping through the pulley and the other end passed downwardly through the slot or opening *g* of section *a*, then passed around the shock and inserted in slot-opening 70 *p* of section *b*. Both ends of the rope are then pulled at the same time until the required compactness of the shock is obtained, when the said ends are released, and the tendency of the shock to open withdraws the rope slightly 75 from the slots. In this backward movement of the rope it catches against the ends of the pivoted locking device, and the tension on the rope causes the members *a* and *b* to gradually assume a horizontal position, when the rope 80 is securely clamped and the device automatically locked. When the shock is bound, the lever is raised and the released rope removed from the open slot *m*.

It will be seen that both ends of a rope 85 circling a shock can be pulled at the same time or either end can be pulled either by one or two men, thus keeping the shock in a vertical position, and when the ends of rope are released the device automatically locks itself. 90

Having thus described my invention, what I claim, and desire to secure by Letters Patent of the United States, is—

1. A rope clamping or securing device consisting of two hinged members having pulleys 95 mounted therein, and a pivotally-mounted rope-clamp between said pulleys having arms extending to close proximity thereto, as set forth.
2. In an automatic rope-clamping device, 100

consisting of two members hinged at their center and carrying pulley-wheels at their ends, a rope-clamping member pivotally mounted between said pulleys having arms extending 5 to a point adjacent said pulleys, and a lever connected with one of said members for unlocking the clamp, as set forth.

3. In a rope-clamping device, consisting of two hinged members provided with pulley-wheels and a rope-clamper pivotally mounted between said wheels having arms extending 10 to a point adjacent thereto, and an unlocking-lever connected with one of said members, whereby both ends of a rope may be pulled at 15 the same time and the device automatically locked by a backward tension on said rope, as set forth.
4. An automatic rope-clamping device, con-

sisting of two members hinged together and having recessed faces, one of said members 20 having extended arms provided with rope-guides, pulley-wheels mounted between said arms, a rope-slot and an unlocking-lever, and the other member having a pulley-slot formed in its end, said slot having rope-guides thereon 25 and a pulley mounted therein and a side opening, and a rope locking or clamping device pivotally mounted between said pulleys and in the said recesses, substantially as set forth.

In testimony whereof I have signed my name 30 to this specification in the presence of two subscribing witnesses.

NELSON HURD FULTS.
